COMBINED COAT HANGER AND BRUSH

William B. Schaefer, Cincinnati, Ohio

Application March 18, 1954, Serial No. 29,598

Term of patent 3½ years

(Cl. D80—8)

To all whom it may concern:

Be it known that I, William B. Schaefer, a citizen of Austria, residing at Cincinnati, in the county of Hamilton and State of Ohio, have invented a new, original, and ornamental Design for a Combined Coat Hanger and Brush, of which the following is a specification, reference being had to the accompanying drawing, forming a part hereof.

Figures 2 and 3 are a front and rear elevational view, respectively, of the design with the hanger arm portions folded to form a brush; and

I claim:

The ornamental design for a combined coat hanger and brush, as shown.
